Water Wheel.

Patented June 2, 1836.

Mooring Attnay, of Lincoln, Comptee.

Letters Patent - Granted June 2, 1836.

The schedule referred to in these Letters Patent and making part of the same, containing a description in the words of the said George Attnay, himself of his improvement in the current wheel which.

To all to whom these Presents shall come. Be it known, that I George Attnay, in the County of Lincoln, State of Ohio, have invented a new and useful horizontal, current water wheel, and that the following is an exact and full description thereof - I have a horizontal shaft sufficiently to contain as many sets of wings as may be deemed necessary for the power required - The shaft is divided to eight or less squares, so each set of wings have two sets of arms, locked round the shaft, sufficiently strong to support the wings when in operation - The front or upper set of arms commence from the lower square of the shaft, the second set from the top of the shaft and are so arranged as to form an angle of forty five degrees with the horizon, when the arm is twisted off to receive the wing, in this way the arms are carried round the shaft until the wheel is completed - with the first set of wings - The second set is shifted half a square and fastened round the shaft in the same way, that this set is again brought to the square as the first, and so on till the number required be fastened to the shaft - This wheel is strongly confined down by cast iron pedestals, the one at the lower end is so cast as to support the end of the gudgeon, at the upper end of the shaft there is a crank working a pitman, which is connected to a lever resting on a pivot in the center, which works another pitman and crank of the size of the first, and carries the power to the necessary set of mica wheels with an upright shaft and suspended the necessary of the lever and pitman. The framing for this wheel, should be strong and heavy and confined to the bottom

of the stream with bolts sufficiently strong to prevent its being moved by high water. — The inside of the frame is made concave to fit the wheel as high as the centre of the wheel, or the wheel may be rimmed and lined on the inside of the running so as to receive the full force and pressure of the current. — A wing dam, to throw a sufficient quantity of water into the wheel, is all that is necessary, it will run at all stages of the water, if calculated at low water mark, strong flood gates the posts of which extend above high water mark, will put it in motion, and stop the wheel at pleasure.

What I claim is my invention and which I am to secure by Letters Patent, is set on the water wheel as before described.
